Inventor:

William H. Walton

United States Patent Office.

WILLIAM H. WALTON, OF BROOKLYN, NEW YORK.

Design No. 4,801, dated April 11, 1871.

DESIGN FOR PRINTED MATERIAL FOR APRONS.

The Schedule referred to in these Letters Patent and making part of the same.

To all whom it may concern:

Be it known that I, WILLIAM H. WALTON, of Brooklyn, in the county of Kings and State of New York, have invented a new Design for Printed Material for Aprons; and I do hereby declare that the following is a full, clear, and exact description thereof, reference being had to the accompanying drawing and the letters of reference marked thereon.

My invention consists in a new, useful, and original design for printing a roll or piece of muslin or other woven fabric in a series of patterns or figures for ladies' or children's aprons, so that the whole piece may be cut into complete apron-patterns by following the outlines printed thereon; and also in printing an ornamental border around each figure or pattern in the series substantially as hereinafter described.

In the accompanying drawing—

Figure 1 represents a section of a piece of muslin printed in apron-patterns of the style usually worn by grown persons, the shoulder-pieces or "brettelles" of which extend only to about the top of the shoulder; and

Figure 2 represents a section of a piece of muslin printed in patterns for long bretelle aprons for children, the shoulder-pieces or brettelles of which pass over the shoulders and are fastened at the back.

In both cases it will be seen that the figures are printed crosswise of the web and alternately reversed, so that the widest part of each pattern will come between the narrowest portions of the adjoining patterns, by which means the patterns come in close contiguity, leaving no waste material between them.

A represents the body of the apron, including the shoulder-pieces or brettelles A'.

B represents the segmental piece to be cut out to form the concavity between the two brettelles, on which the patterns for the pocket-flaps b b and also one or both of the strings or straps c c are printed.

The exterior lines of the patterns serve as guides for cutting out, and by alternately reversing the figures, as shown, I am enabled to cut a whole piece of muslin into aprons with scarcely any waste of material, the pocket-flaps and strings being printed upon and cut from the small fragmentary pieces necessarily cut from the sides of the web to give the aprons an appropriate shape.

Around the border of the apron-pattern and the pocket-flaps I print a broad stripe, a a, in any color that may be preferred, to imitate a binding of ribbon, braid, or tape sewn on in the usual way.

Inside of said broad stripe a any kind of ornamental embroidery may be printed, as represented by scroll-lines a'.

What I claim as my invention, and desire to secure by Letters Patent, is—

1. A piece of muslin or other woven fabric printed in a series of figures or patterns for aprons, said figures being printed in alternately reversed order across the web, substantially as shown and described.

2. A piece of muslin or other woven fabric printed in a series of figures or patterns for aprons, as above described, with an ornamental border around each pattern consisting of a broad stripe in imitation of binding, with or without an additional ornamental border.
